UNITED STATES PATENT OFFICE.

LESLIE F. ZILLES, OF SCHENECTADY, NEW YORK, ASSIGNOR OF ONE-HALF TO JOHN C. GORTON AND THOMAS B. BURNITE, OF SCHENECTADY, NEW YORK.

STEAM-TRAP.

SPECIFICATION forming part of Letters Patent No. 770,210, dated September 13, 1904.

Application filed February 3, 1904. Serial No. 191,862. (No model.)

To all whom it may concern:

Be it known that I, LESLIE F. ZILLES, a citizen of the United States, residing at Schenectady, in the county of Schenectady and State 5 of New York, have invented certain new and useful Improvements in Steam-Traps; and I do hereby declare the following to be a full, clear, and exact description of the invention, such as will enable others skilled in the art to which it 10 appertains to make and use the same, reference being had to the accompanying drawings, and to the letters of reference marked thereon, forming part of this specification.

My invention relates to steam-traps, and 15 has for its objects the construction of a steam-trap in such a manner that the action of the float operates to open and close a steam-controlling-valve mechanism which operates to supply steam to a piston connected with and 20 operating the water-discharge valve of the trap, so as to positively actuate the water-discharge valve both in the opening and closing thereof. These and other features of my 25 invention are hereinafter fully set forth and described, and illustrated in the accompanying drawings, in which—

Figure 1 is a top or plan view of my improved steam-trap. Fig. 2 is a vertical section thereof principally on the line $\alpha\alpha$ in Fig. 30 1. Fig. 3 is an enlarged sectional view of the steam-controlling-valve mechanism.

In the drawings illustrating my invention, A is a hollow shell provided with a steam-inlet opening a , a water-discharge opening a' , 35 and an opening a'' , provided with a cock A' for draining the shell A. In one side of this chamber I provide a cylindrical chamber B, in which a hollow float C moves freely up and down, this chamber B communicating both at 40 the top and bottom thereof with the remainder of the trap, and under the bottom of this chamber B, I provide a stop b to limit the downward movement of the float C.

The top of the shell A, I close by means of 45 a suitable cover D, preferably secured to the shell A by means of bolts d. In the water-discharge opening a' I secure a water-discharge valve E, which consists of a valve-

seat e and a valve-stem e' , operating thereon, and in the upper part of the valve E there is 50 a chamber F, in which a piston connected with the valve-stem e' operates, and in the cap F², closing the top of the chamber F, I make a recess f, adapted to receive a projection f' on the piston F' and which as the piston F' is raised enters the said recess f and compresses the steam or air therein, which 55 operates as a cushion to decrease the impact of the piston F' as it is moved in the chamber F. At the top and bottom of the chamber F 60 I connect small pipes G and G', which lead to a steam-controlling-valve mechanism H, secured in the cover D of the shell A directly over the center of the chamber B. To the top of the float C, I secure a valve-stem I, 65 having a valve I' on its upper end, the upper part of which is hollow and provided with ports i and i' so located that when the float C is down, as shown in Fig. 2, steam enters 70 from a small steam-supply pipe J through the port i in the valve I' and passes up through the chamber in the valve and out through the port i' therein and thence through the pipe G to the valve-chamber F above the piston F' therein, which operates to hold the stem e' 75 firmly upon the valve-seat e of the water-discharge valve E, and when in this position the pipe G', leading from the lower portion of the chamber F, is open to exhaust. When, however, the valve I' is raised by the float C a short 80 distance, the ports i and i' are closed, and a slight further movement of the valve upward brings the depression i² on the side of the valve I' into position to form a connection with the discharge-port h, which allows the steam to 85 escape from the upper part of the chamber F through the pipe G, and the further upward movement of the float C and valve I' brings the annular groove i³ thereon into line with the pipes J and G', so that steam passes there- 90 through to the lower part of the valve-chamber F and operates on the piston F' to raise the valve-stem e' off of the seat e, which allows the water to escape therethrough, the valve being thus held open until the float C 95 moves the valve I' downward far enough to

discharge the steam from the lower part of the chamber F through the pipe G' and escape-ports i^2 and h and again turns the steam through the pipe G to the upper part of the 5 valve-chamber F, as before. This operation of the mechanism being automatic, operates as described to discharge the water from the trap-shell A as often as it accumulates therein.

Having thus fully described my invention, 10 so as to enable others to construct and utilize the same, what I claim as new, and desire to secure by Letters Patent of the United States, is—

1. The combination in a steam-trap of a shell 15 having a steam - inlet and a water - discharge opening, valve mechanism in the water - discharge opening, a cylinder and double-acting piston mechanism connected with said valve mechanism, a steam-controlling valve adapted 20 to supply steam alternately to either side of the piston controlling the water - discharge valve, an integral stem depending from said steam-controlling valve, and a float connected to said stem and operating said valve, sub- 25 stantially as set forth.

2. The combination in a steam-trap, of a shell having a steam - inlet, and a water - discharge opening, a steam-actuated valve in said water- discharge opening, a hollow piston-valve mechanism for controlling and supplying steam to 30 and operating the water - discharge valve, a float operating in a supplementary chamber within the trap-shell, and a valve-stem connecting said float with the hollow piston-valve mechanism, substantially as and for the purpose set forth.

3. The combination in a steam-trap, of a shell having a supplementary float - chamber, a

steam - inlet and a water - discharge opening 40 therein, a valve in the water-discharge opening, a cylinder and piston connected with said valve, pipes leading from said cylinder above and below the piston therein, a hollow piston- valve mechanism connected with said pipes for controlling and supplying steam to said cylinder, a valve-stem connected directly with and operating said piston-valve, and a float in 45 said float-chamber connected with and operating said valve-rod, substantially as set forth.

4. The combination in a steam-trap, of a shell 50 having a supplementary float-chamber therein, and a steam-inlet, a water-discharge opening and a drip-cock opening therein, a valve in the water-discharge opening, a cylinder in 55 said valve a piston therein connected with and operating said valve, a steam-controlling-valve mechanism, a hollow valve therein, a pipe adapted to communicate therewith and connecting the valve with the cylinder on the water-discharge valve above piston therein, 60 an annular groove around the valve in the steam - controlling - valve mechanism adapted to communicate with a pipe leading to said cylinder below the piston therein, whereby the raising and lowering of the float operates 65 the steam - controlling valve to supply the steam to the cylinder on the water-discharge valve, and actuates the piston therein to open and close said valve, substantially as and for the purpose set forth.

In testimony whereof I affix my signature in presence of two witnesses.

LESLIE F. ZILLES.
